UNITED STATES PATENT OFFICE.

ALBERT E. ROCKEY, OF DETROIT, MICHIGAN.

DESIGN FOR A COFFEE CREAMER.

Application filed August 17, 1925. Serial No. 14,503. Term of patent 14 years.

To all whom it may concern:

Be it known that I, ALBERT E. ROCKEY, a citizen of the United States, residing at Detroit, in the county of Wayne and State of Michigan, have invented a new, original, and ornamental Design for Coffee Creamer, of which the following is a specification, reference being had to the accompanying drawings, forming part thereof.

Fig. 1 is a plan view of a coffee creamer showing my new design.

Fig. 2 is an elevation thereof.

I claim:

The ornamental design for a coffee creamer as shown.

ALBERT E. ROCKEY.
